UNITED STATES PATENT OFFICE.

MORRIS KREISWIRTH AND SAMUEL GRONER, OF NEW YORK, N. Y.

DESIGN FOR A FINGER RING.

60,910.

Specification for Design. Patented Apr. 25, 1922.

Application filed January 25, 1922. Serial No. 345. Term of patent 7 years.

To all whom it may concern:

Be it known that we, MORRIS KREISWIRTH and SAMUEL GRONER, citizens of the United States, residing at New York city, in the county and State of New York, have invented a new, original, and ornamental Design for a Finger Ring, of which the following is a specification, reference being had to the accompanying drawing, forming part thereof.

Figure 1 is a side view.

Figure 2 is an edge elevation, and

Fig. 3 is a top plan view of a finger ring, showing our new design.

We claim:

The ornamental design for a finger ring as shown.

MORRIS KREISWIRTH.
SAMUEL GRONER.
